United States Patent Office.

VITALIS HIMMER, OF BROOKLYN, NEW YORK.

Letters Patent No. 86,751, dated February 9, 1869.

IMPROVEMENT IN STEM-WINDING WATCH.

The Schedule referred to in these Letters Patent and making part of the same.

To all whom it may concern:

Be it known that I, VITALIS HIMMER, of Brooklyn, in the county of Kings, and State of New York, have invented a new and improved Stem-Winding Watch; and I do hereby declare that the following is a full, clear, and exact description thereof, which will enable those skilled in the art to make and use the same, reference being had to the accompanying drawings, forming part of this specification, in which—

Figure 1 represents a plan or face view of my improved watch.

Figure 2 is a detail face view of the drum.

Figure 3 is a detail sectional view of the same, taken on the plane of the line $x x$, fig. 2.

Figure 4 is a detail section, taken on the line $y y$, fig. 1.

Similar letters of reference indicate corresponding parts.

The object of this invention is to produce a stem-winding watch, which is so arranged that the spring cannot be overwound, and that if it is wound up to the requisite limit, the gearing-connection between the drum and the stem will be automatically and effectually interrupted.

Heretofore automatic disengaging-devices were employed by which the end of the spring was detached from the drum, but these invariably injured the spring, as, by such frequent abrupt stoppages, the repeated shocks either broke or spoiled the spring.

My invention consists more particularly in the use of a pin fitted through the wheel that is mounted on the spindle of the main-spring, and in a fingered wheel resting upon and turning with the drum. During the revolution of the aforesaid spindle, while the main-spring is being wound up, the pin is carried around and against the fingers of the wheel on the drum, thereby turning said wheel. When the main-spring is wound up, the pin again strikes the fingered wheel, and travels up on an inclined edge formed thereon. It is thereby raised and pushes the wheel that connects the spindle-wheel with the stem up out of gear, so that the stem can be turned at pleasure without affecting the spring.

The invention consists, also, in a novel device for combining the winding and setting-apparatus.

A, in the drawing, represents the case of a suitable watch.

B is the upper plate under the dial.

C is the stem, carrying a crown or toothed wheel, a , which meshes into a wheel, b , that turns on a spindle projecting from the plate B.

D is an L-shaped spring-plate, pivoted near one end, by a pin, e , to the plate B, a hook or projection, d , being formed near its pivoted end.

¹ In the plate D are the bearings for a small toothed wheel, e , which meshes into the wheel b , and also into a toothed wheel, f , that is mounted on the spindle, E, of the main-spring, as indicated in fig. 3.

The non-pivoted end of the plate D rests on the wheel f , as shown.

A spring, g , serves to so hold the plate that the wheel e is kept in gear with b and f .

F is an L-shaped or triangular frame pivoted, at h , to B, and carrying on its free end a toothed wheel, i .

It has a hook, j , that rests over the hook, d , of the plate D, as in fig. 1.

G is a cam pivoted to the plate B, or to the case A, near the edge of the watch.

It has a projecting handle, by means of which it can be turned.

When this handle is turned out, the cam presses against the frame F, swinging the same around its pivot, h , so as to throw the wheel i against the wheel k on the minute-hand spindle H, thereby producing a connection between the wheels b and k , and allowing the setting of the watch.

The same motion of the frame F also serves, by bringing the hook j against the projection d , to swing the plate D, so as to carry the wheel e away from b and f , to disconnect the winding-apparatus.

When the handle of the cam G is turned down again, as in fig. 1, the frame F is, by means of a spring, l , brought back to its original position, in which the wheels i and k are disconnected, as shown, and at the same time the plate D is, by the action of the spring g , turned down so as to bring the wheels b e f into gear with each other.

I is the drum, in which the main-spring of the watch is contained.

Upon its face is fitted a wheel, J, which has four (more or less) fingers, m , as shown in fig. 2.

L is a pin fitting loosely through the wheel f , so as to rest with its lower end upon the face of the drum I, while its upper end is under the spring-plate D.

While the watch is running, the wheel J is carried around with the drum, without having any effect upon the operation of the works; but when the watch is wound up, the pin L is carried around with the winding-wheel f , and strikes once during every revolution of the said wheel f , against the wheel J, or, rather, against one of its fingers. Thereby the wheel J is turned, and at the next revolution of f , the pin L strikes the next finger of J, &c., until, when the spring is nearly or quite wound up, the pin L comes against an inclined edge, n , of the wheel J, as shown in fig. 2.

Being raised by ascending this incline, the pin also raises the end of the plate D, and with it the wheel e , disengaging thereby the latter from b and f .

The connection between the stem and spring is thus most effectually interrupted, and the spring can never be injured or broken by overwinding.

To make the disengagement of the wheel e still more certain, the plate D is brought in contact with the head of a spring-pin, o .

This head is thicker on its upper than on its lower side, as indicated in fig. 4, and when the plate D is

raised by the aforesaid action of the wheel J and pin L, its edge sliding up on the inclined face of o, it is thrown aside by said pin, so that the wheel e must be entirely out of gear.

When the wheel e is thus disengaged, the watch continues to operate, the slow rotation of the drum pulling the wheel J from under the pin L, reinstating thereby all the parts in their original positions and allowing the spring to be again wound up until the pin L is again raised.

The wheel f is prevented from turning in the wrong direction by means of pawls p p, as shown.

I claim as new, and desire to secure by Letters Patent—

1. The application of the pin L and fingered wheel J to the works of a stem-winding watch, for the purpose of preventing overwinding of the same, as set forth.

2. The fingered wheel J, having the incline n and fitted upon the drum I, in combination with the pin L, fitted through and turning with the winding-wheel f, spring-plate D, and wheel e, all made and operating substantially as herein shown and described.

3. The device set forth in the foregoing clause, in combination with the spring-pin o, for throwing the plate D aside when it is raised, as set forth.

4. The swinging L-shaped plate D, having the wheel e and the hook d, in combination with the L-shaped or triangular swinging frame F, having the wheel i and the hook j, all arranged and operating substantially as and for the purpose herein shown and described.

VITALIS HIMMER.
